UNITED STATES PATENT OFFICE.

ALFRED E. STAFFORD, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed February 7, 1928. Serial No. 252,472.

This invention relates to feeler mechanisms for looms and is more particularly directed to such mechanisms wherein the feeler is of the side slipping type.

5 The side slipping type of feeler is well adapted for use in connection with filling wound bobbins where the feeler contacts with the bobbin and slips or slides along the bobbin surface when the filling is substantially exhausted on a detecting beat. When such form of feeler, however, is employed in connection with filling wound upon paper cop tubes the roughness of the tube itself may prevent the feeler from side slipping even 10 though the filling be substantially exhausted, and this same characteristic is present at times where the feeler is cooperating with a filling wound bobbin, owing to the fact that the bobbin surface after repeated use may 15 become roughened.

It has heretofore been proposed to provide a side slipping feeler with a shuttle feeling finger, which, when the filling is substantially exhausted, may engage the front wall of the 20 shuttle on a detecting beat and facilitate the side slipping movement of the feeler by longitudinal movement of the finger along the shuttle wall.

The amount of filling that remains upon 25 the filling carrier on replenishment constitutes waste, which, it is desirable, of course, to minimize, and in such cases, therefore, the shuttle feeling finger has been mounted for adjustment on the feeler by a threaded connection with a lug carried by the feeler and locked in its adjusted position by one or more locking nuts. The head of the shuttle feeling finger is preferably of rounded character and of considerable vertical extent in order to insure 30 proper contact with the front wall of the shuttle when filling is substantially exhausted, but where the shuttle feeling finger has a threaded connection with its support upon the feeler, it requires substantially either a full rotation of the feeling finger or 35 partial rotation thereof when the locking nuts are released and the feeler is to be adjusted. Thus the amount of adjustment of the shuttle feeling finger depends upon rotation 40 of the feeling finger, and since the head of the feeling finger must always be properly positioned in a vertical plane to properly contact with the wall of the shuttle, the amount of adjustment of the shuttle feeling 45 finger required by the constructions so far in

use will frequently produce more waste than is desirable.

One of the objects of the present invention is to provide a side slipping feeler with a shuttle feeling finger which may be adjusted 60 without the necessity of rotating the feeling finger, thereby permitting great nicety of adjustment either to very small or larger amounts and consequently controlling the amount of waste that will remain upon the 65 filling carrier upon replenishment.

In accordance with the present invention, the side slipping feeler is provided with a vertically extending standard having an unthreaded aperture of larger diameter than 70 the diameter of the threaded shank of the feeling finger and adjusting nuts bearing upon the front and rear surfaces of the standard, whereby, upon manipulation of the nuts the feeling finger may be moved frontwardly 75 or rearwardly minimum amounts while maintaining the head of the shuttle feeling finger in its normal operating position relative to the front wall of the shuttle.

A further feature of the present invention 80 consists in means for preventing rotation of the shuttle feeling finger on its longitudinal axis during adjustment of the feeling finger.

The invention and novel features thereof will best be made clear from the following 85 description and the accompanying drawings of one good form thereof.

In the drawings:

Fig. 1 is a plan view showing a side slipping feeler containing the present invention, 90 and part of a shuttle containing filling;

Fig. 2 is a section on the line 2—2 of Fig. 1;

Fig. 3 is an exploded view of the side slipping feeler and shuttle feeling finger showing the parts in separated relation;

Fig. 4 is an enlarged sectional view on the line 4—4 of Fig. 1; and

Fig. 5 is a side sectional elevation showing the side slipping feeler of the present invention in use with a cop tube for carrying the 100 filling in the shuttle.

As hereinbefore noted, the feeler is of the side slipping type and may be given its side slipping movement either by the forward pressure of a surface on the lay or by spring means, both of such expedients being now generally known in the art. As illustrating a preferred embodiment of the feeler mechanism, the feeler is of the floating type, which may be substantially as shown and described 105 110

in the patent to Brown and Repass, No. 1,593,426, dated July 20, 1926.

- The feeler stand 1 is mounted as usual upon the loom frame, as indicated in Fig. 2, 5 through the instrumentality of a bracket 2, and an adjusting screw 3 may be passed through an opening 4 in the top portion 5 of the bracket so that the feeler stand may be given a general adjustment towards and 10 from the front of the loom. Mounted in the feeler stand is the feeler 6, the rear end portion 7 of which is provided with a series of teeth adapted to engage the filling on detecting beats when a working supply is present in 15 the shuttle, and thereby hold the side slipping feeler from side slipping movement. The front portion 8 of the feeler is laterally extended and the end 9 of the lateral extension is adapted to engage a stop 10 on the feeler 20 stand when the feeler is in its rearward feeling position, as indicated in Fig. 1, and a spring 11 is attached to the laterally extending arm 8 and to the rear portion of the feeler stand, normally acting to move the feeler into 25 its rearward feeling position. Associated with the feeler and feeler stand is a transmitter 12 which is associated with a train of mechanism for effecting replenishment of filling when the feeler is given its side slipping movements on a detecting beat. The parts so far described are substantially the same, or may be, as shown and described in 30 the Brown and Repass patent above mentioned.
- The shuttle 13 is provided with the usual holding jaws 14 to engage the rings 15 of the filling carrier which, as shown in Fig. 1, may be formed as a bobbin having the filling 16 wound thereon.
- The fine adjustment which is rendered possible by the present invention may be advantageously employed in connection with cops wherein the filling is wound upon short paper cop tubes, a condition which is illustrated by 45 Fig. 5. In either case, however, that is whether the filling be wound upon a bobbin or upon a cop tube, the present invention provides means for fine adjustment of the feeler mechanism to the end that the amount of 50 waste on the ejected filling carrier, whether it be a bobbin or cop tube, will be of minimum amount.
- Secured to and extending vertically upward from the feeler 6 by solder or welding 55 is the standard 17 which is positioned near the tip portion of the feeler, and such standard is provided with an aperture 18 which is unthreaded and of larger diameter than the threaded shank 19 of the shuttle feeling finger. The shuttle feeling finger is provided 60 with a rounded head 20 of substantially vertical extent to present a face adapted to contact with the front wall of the shuttle when the filling therein has become substantially 65 exhausted.

At the front and rear of the standard 17, the threaded shank 19 of the feeler finger has threaded thereto adjusting nuts 21 and 22, the construction being such that the threaded shank 19 of the shuttle feeling finger may 70 be adjusted longitudinally by manipulation of the adjusting nuts 21 and 22 while the shuttle feeling finger itself is restrained from rotating movement. The effect of this is that the amount of adjustment towards and from 75 the front of the loom which may be given to the shuttle feeling finger can be made without rotating the shuttle feeling finger or disturbing the relation between the contacting face or head 20 and the front wall of the shuttle with which the feeling finger cooperates, and such adjustment may be of very small or minimum amount, to the end 80 that the amount of waste left upon the filling carrier upon replenishment of filling will be 85 of minimum amount.

A further feature of the present invention provides means for preventing rotative movement of the shuttle feeling finger during adjustment, and, as indicated in the present 90 form of the invention, the standard 17 is provided with a threaded opening 23 through which extends a threaded pin 24, the lower end portion 25 of which is adapted to engage a longitudinal groove 26 formed in the 95 threaded shank of the feeling finger, the result being that when the adjusting nuts 21 and 22 are manipulated for adjustment of the feeling finger, the latter will be held from rotative movement and the head portion 20 thereof be maintained in its desired cooperative relation vertically with the front wall 100 of the shuttle.

Where the diameter of the aperture 18 of the standard 17 is materially greater than the 105 diameter of the threaded shank 19 of the feeling finger, it is desirable that the feeling finger be centralized in the opening 18 and maintained in central relation therewith during operation and during adjustment. To 110 this end the adjusting nuts 21 and 22 are each provided with an inwardly extending portion 27, 28, of substantially the same diameter as the aperture 18, so that when the parts are assembled, as indicated in Fig. 4, the projections 27 and 28 of the adjusting nuts will 115 centralize the shuttle feeling finger. If desired, the projections 27 and 28 on the adjusting nuts may be internally threaded in continuation of the threads on the nuts, though 120 this may not always be necessary provided the internal diameter of the projections 27 and 28 is greater than the diameter of the shank 19.

During the weaving operation with a working 125 supply of filling in the shuttle, the tip portion 7 of the feeler will enter the shuttle through the opening 29 and contact with the filling and then be moved frontwardly, while the filling itself restrains side slipping 130

movement of the feeler, and this action will continue whether the filling be wound upon a bobbin or cop, so long as a working supply is present in the shuttle. When the filling has become substantially exhausted and replenishment should be called, the face of the head 20 of the feeling finger will engage the front wall of the shuttle, and, in the present instance, the forward pressure of the shuttle upon the feeling finger will effect side slipping movement of the feeler as the head of the feeling finger travels along the front wall of the shuttle, to thereby effect replenishment of filling.

Under the action described, the feeler becomes substantially a measuring feeler, that is, it measures the diameter of the filling in the shuttle to finally permit the front wall of the shuttle to engage the shuttle feeling finger when it enters the shuttle sufficiently far owing to depletion of the filling. By adjustment of the shuttle feeling finger through the mechanism described it will at once be obvious that small or minimum amounts of adjustment may be made to effect contact of the shuttle feeling finger with the shuttle without disturbing the relation of the head of the feeling finger and the shuttle wall, with the result, also, that a minimum amount of waste may be left upon the filling carrier when replenishment is effected.

What is claimed is:

1. A feeler mechanism for looms having a side slipping feeler with a toothed engaging tip, in combination with a vertical standard extending from the feeler near its tip end and having an unthreaded aperture, a shuttle feeling finger having a threaded shank of less diameter than the diameter of the unthreaded aperture and provided with a rounded shuttle engaging head frontward of the toothed engaging tip adapted to be encountered by and slip laterally upon the front wall of the shuttle when the feeling tip does not make restraining contact with the filling, and adjusting nuts threaded upon the shank of the shuttle feeling finger and having centering projections extending into the unthreaded aperture to maintain the feeling finger centered in the aperture.

2. A feeler mechanism for looms having a side slipping feeler with a toothed engaging tip, in combination with a vertical standard extending from the feeler near its tip and having an unthreaded aperture, a shuttle feeling finger having a threaded shank of less diameter than the diameter of the unthreaded aperture and provided with a rounded shuttle engaging head frontward

of the toothed engaging tip adapted to be encountered by and slip laterally upon the front wall of the shuttle when the feeler tip does not make restraining contact with the filling, means for preventing rotative movement of the shuttle feeling finger in the aperture of the standard, and adjusting nuts in the front and rear of the standard and threaded upon the shank of the feeling finger for moving it in the aperture of the standard while restrained from rotative movement.

3. A feeler mechanism for looms having a side slipping feeler, in combination with a vertical standard mounted on the feeler and having an unthreaded aperture, a shuttle feeling finger having a threaded shank of less diameter than the diameter of the aperture and extending loosely therethrough, a head on the shuttle feeling finger having a shuttle engaging face, means for centering the feeler finger in the unthreaded aperture, and adjusting nuts for moving the shuttle feeling finger longitudinally through said aperture while restrained from rotative movement that the shuttle engaging face of the head may not be rotatively displaced as the feeling finger longitudinally through said aperture of the standard.

4. A feeler mechanism for looms having a side slipping feeler, in combination with a vertical standard mounted upon the feeler and having an unthreaded aperture, a shuttle feeling finger having a threaded shank extending loosely through said aperture, and provided with a longitudinal groove, means upon the standard engaging said groove to prevent rotative movement of the feeling finger, and adjusting nuts for moving the shuttle feeling finger any amount longitudinally in the unthreaded aperture of the standard while restrained from rotative movement.

5. A feeler mechanism for looms having a side slipping feeler, in combination with a vertical standard mounted upon the feeler and having an unthreaded aperture, a shuttle feeling finger having a threaded shank extending through said aperture, and adjusting nuts provided with projections extending into the unthreaded aperture to centralize the shuttle feeling finger that the shuttle feeling finger may be adjusted fine amounts while centralized in the standard by movement of the shuttle feeling finger by the adjusting nuts while the feeling finger itself is restrained from rotative movement.

In testimony whereof, I have signed my name to this specification.

ALFRED E. STAFFORD.
